UNITED STATES PATENT OFFICE.

FRANZ PUENING, OF PITTSBURGH, PENNSYLVANIA.

DISTILLING CARBONACEOUS MATERIAL.

Application filed November 6, 1922, Serial No. 599,177. Renewed January 14, 1928.

This invention relates to the art of distilling carbonaceous material, such as bituminous coal, lignite, shale, peat, or other carbonaceous material which forms coke. An object of the invention is to effect the distillation of such carbonaceous material at low temperatures, in accordance with the principle of low temperature distillation disclosed in one embodiment in my prior application for Letters Patent of the United States, filed February 11, 1922, Serial No. 535,790, and in another embodiment in my prior application for Letters Patent of the United States, filed February 11, 1922, Serial No. 535,791, by causing the processional advance of masses of such material from a charging station to a discharging station and through a region of distillation, while such masses are in contact with preheated walls of high heat-conductive capacity, and successively forming and discharging such masses, and collecting the products of distillation.

In carrying out the distillation there are employed, as the medium for effecting the transfer of the distilling heat to the material to be distilled, heating walls of a substance of high enough heat conductivity to effect a rapid transfer of the distilling heat to the material, for example, bituminous coal. It is preferable, however, to employ metal heating walls, iron, in any one of its several forms, being especially suitable because of its great specific weight, its high heat conductivity, its good wearing qualities, its resistance to deterioration when subjected to rapid temperature changes and the influence of hot gases, and lastly, because of its cheapness. The invention, however, is not limited to the employment of iron as the material for the heating walls.

These heating walls are first exposed to the action of hot gases to store in them the heat which is subsequently employed for effecting the distillation of the material. Any hot gases may be employed, provided that they are not of such a nature as to readily injure the heating walls. In any case, the temperature to which the heating walls may be heated is limited by the resistance of the material of which they are composed to oxidize or be otherwise impaired at high temperatures. In case iron is employed, however, the walls may be heated to a tempera-

ture of about 1400° F. in an atmosphere of well burned gases, without unduly exposing the iron to deterioration.

With iron heating walls heated to a surface temperature of 1400° F., distillation of the coal may be effected by bringing the coal into direct contact with such previously heated walls. The coal to be distilled may be either at ordinary atmospheric temperature, prior to the time of contact with the heating walls, or may be preheated, if desired. At the moment of contact, coal quickly absorbs the peak of the heat stored in the surface of the walls and in the portions of such walls just below its surface. The particles of the coal in contact with the heating walls are thus rapidly heated, the heat penetrating into the interior of the coal. During the heating up stage, a dry skin of coke is formed on the coal, thereby permitting ready separation of the coal from the walls at the completion of the distillation operation. As the heat transfer from the walls to the coal progresses, the flow of heat into the coal diminishes in rate, along with the approach of the coal and the heating walls into an equilibrium of temperature. In order to avoid an impractical slowing up of the heat transfer, after the initial rapid heat absorption by the coal, the weight of the heating walls, with respect to the coal being distilled, is regulated so that the storage capacity for heat of the walls is in excess of the heat required to bring the coal to the required final temperature. The final temperature varies, of course, with different coals and with the other materials available for treatment by the distillation process of the invention. For many of such materials, however, a satisfactory final temperature is approximately a thousand degrees F. and the process of low temperature distillation would be completed at that temperature. It requires about 400 B. T. U. per pound of material, in order to heat commercial grades of bituminous coal to a final temperature of a thousand degrees F. In order to attain such a final temperature, a maximum temperature drop of the heating walls from 1400° F. to a thousand degrees F. is available. Between 1400° F. and a thousand degrees F., iron, for example, has a specific heat of approximately 0.148. Therefore, (1400 - 1000)

80
85
90
95
100
105

$\times 0.148 = 59$ B. T. U. are freed for absorption by the coal, when one pound of iron drops from 1400° F. to a thousand degrees F. Inasmuch as 400 B. T. U. are required for one pound of coal, 400 divided by 59 equals 6.77 pounds of iron which are required to furnish sufficient heat for elevating one pound of coal to a final temperature of approximately 1000° F. In order to compensate for the slowing down of the heat transfer, as above explained, it is preferable to employ approximately twice as much iron as the theoretical minimum, which would be approximately 14 pounds of iron for each pound of coal to be distilled.

By preheating the coal or drying it before bringing the coal into contact with the hot iron, the amount of heat required for the distillation process may be materially reduced. This would permit the process to be carried on with a smaller quantity of iron. Even when preheating of the coal is employed, it is preferable to employ enough iron in order that the heat available for distillation be about twice the amount of the theoretical minimum.

The invention further consists in coking carbonaceous material by moving the retorts or coking chambers progressively through a heating region and then through a distillation and coking region, charging material to be coked into the heated retorts, then causing said material to be coked by the heat of the retort walls while passing through said coking region, then discharging the coked material from the said retorts, and repeating said steps of heating, charging, coking and discharging in a continuous cycle. Preferably, the cycle of said steps are performed during and by the movement of an endless series of coking retorts. The process may be performed with intermittent movement of said retorts.

An important feature of my apparatus for carrying out the process is improved automatic means for conveying the coking chambers for the purpose of the alternate heating and coking operations, and for the charging and discharging of the material.

In addition to the general objects recited above, the invention has for further objects such other improvements and advantages in operation and results as may be found to obtain in the processes or apparatus herein-after described or claimed.

In the accompanying drawings, forming a part of this specification, and showing for purposes of exemplification, a preferred form and manner in which the invention may be embodied and practiced, but without limiting the claimed invention to such illustrative instance or instances:

Figure 1 is a central vertical longitudinal section of the principal parts of a coking furnace adapted for the performance of and

embodiment, the invention, certain of the parts being shown in elevation on line A—A of Fig. 2;

Fig. 2 is a plan view of the same, partly broken away to indicate the interior construction;

Fig. 3 is a vertical sectional view showing the charging means, on line E—E of Fig. 2;

Fig. 4 is a similar view of the same on line D—D of Fig. 2;

Fig. 5 is a vertical sectional view at the discharging station, on line B—B of Fig. 2;

Fig. 6 is a similar section, on line C—C of Fig. 2;

Fig. 7 is a vertical section on line F—F of Fig. 2, showing the distillate sealing means at a point between the discharging station and the heating chamber.

Fig. 8 is a diagram illustrating the arrangement of the system of actuating means for automatically controlling the charging and discharging operations.

Figs. 9 to 13 inclusive are diagrams illustrating the electric switch operations when the machine is started with the pusher in the highest position, with the brakes, which control the movement of the coking chambers, released.

Figs. 14 to 18 inclusive are diagrams illustrating the same, when the controlling pawl drops into its notch and throws the switches to set the brakes and cause the pusher to travel down.

Figs. 19 to 23 inclusive are diagrams illustrating the same, when the pusher reaches its lowest position and throws the switches which control its own movement.

Figs. 24 to 28 inclusive are diagrams of the same, when the pusher has reached its highest position and it has thrown the switches to cause the release of the brakes for the further movement of the coking chambers.

In its present embodiment, the invention is applied to the low temperature distillation of bituminous coal, for producing coherent coke, such as is available for domestic heating purposes. For convenience, the ensuing description will be confined to this application of the invention. The novel features and improvements of the invention are, however, applicable to the distillation of other carbonaceous material, for example, to any of the other materials hereinabove mentioned; hence, the scope of the invention is not confined to the specific use and specific embodiment herein described as an illustrative example.

The furnace is divided into two sections, a heating section and a distillation and coking section, by means of seals on the top, side and bottom of the coking chambers near the discharging station, and a seal on the side at the filling station, while material to be distilled does or may form a seal at the top and

bottom of the filling station. These practically prohibit the mixing of the hot gases in the heating section, with the vapors in the coking section.

5 The furnace is stationary, while the metallic heating walls rotate, absorbing heat as they pass through the heating section and give off heat to the material being treated as the pass through the coking section. The 10 raw material is fed by gravity from a hopper. The operation is continuous but the heating walls travel with an intermittent motion, stopping each time an opening between heating walls comes directly underneath the center line of the discharging station, allowing the pusher to pass down through the heating wall opening and free the coking chamber of the coked material; after the pusher has come back up the machine is again free to 15 rotate. The coke, having been pushed into the discharger below, is thus removed from the furnace.

The furnace is constructed of fire clay bricks and covered with flat arch brick hung 20 from a steel superstructure making it easy to remove a few bricks from the top for inspection or repair; also an inspection door is provided on the side of the furnace, this door being constructed of bent plates with insulating material between, preventing excessive heat losses due to radiation and making 25 it light to handle. On the coking side of the furnace a vapor outlet is provided near the top of the furnace, from which the vapors of 30 distillation may be led to any suitable by-product recovery apparatus.

Referring to the drawings, G indicates an 35 endless series of coking retorts or chambers having side heating walls formed of metal or other suitable material. In the illustrated embodiment of the invention, the series is 40 of circular and annular arrangement and the retorts turn progressively and intermittently in horizontal planes around the vertical axis 45 of the shaft 1 and in a clock-wise direction (viewed in Fig. 2). One or more of the coking retorts or chambers, with their contiguous heating walls may be formed in a single unit, and as illustrated (Fig. 2) each 50 unit comprises four retorts and four half-retorts. The retorts 4 are preferably of such interior shape as to hold the material to be distilled in the form of thin bodies which are extended in directions parallel with the contacting and heating walls of the retorts. The 55 wall-heating region or chamber J of the apparatus is the annular space which extends from the discharging apparatus I to the charging apparatus H in said Figure 2, at the 60 left of said Fig. 2; and the coking region or chamber K is the annular space which extends from the charging apparatus H to the discharging apparatus I, at the right of Fig. 2. Coal or other material suitable 65 to be coked or distilled is charged into

the retorts 4, by a charging apparatus or device H (Figs. 3 and 4) arranged at or near the line D, and this is done at the times when said receptacles successively and momentarily come to rest under said charging 70 device. Said charging device comprises a hopper 63 carried by beams and angles 64, 65 (Fig. 3). At the same periods of rest the coked material is discharged from the retorts, one after another, by a discharger I 75 (Figs. 5 and 6) arranged at or near the line B. While the empty retorts are passing from the discharging station to the charging station and through the heating region their contiguous walls are heated to a coking temperature, for the desired result, by hot gases which are caused to flow through the retorts, but during the coking period, the bottom of the retorts are closed by a plate or floor which 80 extends under them.

The central vertical carrier shaft 1 has a bottom bearing 17 mounted on the concrete base 18 and the upper part of said shaft is held in a bearing 19 which is carried on channel beams 20, the ends of which are fastened 90 to the superstructure which carries the furnace roof. The series G of coking receptacles or walls 4 are attached to a ring 3 (Fig. 1) the inner bottom portion of said walls resting on the top edge of a downwardly and inwardly beveled ring 5 (Fig. 4) which is attached to the outer surface of said ring 3. The upper inner portions of the receptacles 4 are connected with the upper part of the ring 3 by means of T-headed bolts 6 the shanks of 100 which rest in notches in the top of the main ring 3 with their inner heads engaged within this ring, and with their outer T-heads engaged in suitably shaped openings in the upper parts of said receptacles 4. 7 is a heat insulating material of suitable character interposed between the ring 3 and said coking receptacles which insulating material may be tucked around and over the bolts 6 as seen in Fig. 4. The weight of this carrier is sustained 105 principally by an angle ring 8 (Figs. 1 and 5) which is attached within the lower part of the ring 3 and rests on rollers 9. Such rollers are arranged at proper intervals around under the path of the ring 8. The rollers have their 110 axles mounted in outer and inner rings 10 and 11, whereby the rollers are spaced apart while they travel on the track 12. This track is arranged in a liquid seal 13 into which dips a gas cut-off ring 14, this ring being attached to 115 the carrier all around the under part of the same. The main carrier ring 3 is connected with the shaft 1 by radial or cross girders 2 which are attached to head plates 21 and bearings 21', the latter embracing the shaft 1. It 120 will be understood that the shaft may rotate in its bearings 17 and 19, or may remain fixed and the carrier bearings 21' may turn on said shaft. 15 is an upper liquid seal extending 125 around the carrier and supported on the gir- 130

ders 2, into which seal dips a ring 16 fixed to the superstructure. By these upper and lower liquid seals the hot furnace gases by which the coking chambers are to be heated are kept from passage inward beyond the heating and coking regions, or beyond the coking chambers:

At the left hand side of Fig. 1 are shown upper and lower ducts 42 and 43 through which furnace gases which have been heated to a temperature high enough for the purpose flow upwardly or downwardly through the coking receptacles 4. The coking retorts at the left hand side of Fig. 1 are in the heating region of the apparatus and are open at the bottom for the free passage of the heating gases in contact with the heating walls. The retorts at the right hand in said figure are in the coking region where the previously heated retort walls give up their heat to the coal which has been charged into the retorts. Along under said coking or distilling region is arranged a fixed plate 66 which prevents escape of the coal or coke from the bottoms of the charged retorts until they arrive at the discharging station, at which point the plate 66 terminates (Fig. 6). The carrier for the coking chambers and their contiguous heating walls is operated by the motor 40, speed reducer 39 which is connected with the motor by a magnetic clutch 41, the shaft 38, the pinion 37, the gear wheel 36, the shaft 35, the vertical bevel gears 34, the horizontal bevel gears 33, the vertical shafts 31, and the pinions 30. The pinions 30 mesh with a toothed ring 29 attached to the rotary carrier. The carrier is thus turned in horizontal planes whenever the clutch 41 is made operative. This is effected at the time when the pusher 50, after discharging the coke from a chamber 4, returns upwardly to its highest position (Fig. 5), whereupon a rod 57 moving with the pusher and carrying a lever 58 causes said lever to close the electric switch 2^a (Fig. 9), the switch 1^a having been closed by the lever 87 as below explained), and causes the clutch 41 to couple the motor 40 with the speed reducer 39. The carrier with its series of coking chambers 4 is now turned until said clutch is released. This release is effected primarily by a pawl 84, which, as soon as the next chamber 4 containing coked material arrives under the pusher, drops under the impulse of a spring 86 into a notch 83 (Fig. 2). The walls 4 are provided with an endless circular series of these notches, one for each coke-containing space or retort so that each of said spaces is successively stopped at the pusher station. This movement of the pawl causes a lever 87 to move outwardly, and, among other functions, this movement of the lever causes the opening of the switch 1^a (Fig. 14) and the disengagement of the clutch 41.

The carrier may now come to rest but I prefer to insure a prompt stopping of the

same by fluid-actuated brakes 25 (seen in Fig. 1), which may be caused to bear upward against a ring or shoe 22 attached to the bottom of the carrier. The brakes are thus actuated to arrest the carrier by the admission of fluid (water for example) under the pistons 23 in cylinders 24, said fluid overcoming the brake-releasing springs 26 and being supplied by a pipe 44.

The fluid is released to have this action by a solenoid 3^b (Fig. 8) which opens an inlet valve V in the pipe 44 and closes an outlet valve V' to the pipe 44' by which the brake cylinders communicate respectively with the pipe 44 and the atmosphere, and this solenoid is electrically energized for the purpose by a switch 7^a which at this time is closed (as seen in Fig. 17) by the described outward movement of the lever 87. The brakes 25 remain set while the pusher 50 makes its downward and upward movements. These movements are caused by the piston and rod of the pusher cylinder 49, said rod being attached to the pusher (Fig. 5), and pressure fluid being supplied above said piston by a pipe 45, having an outlet 46, to depress the pusher, and being supplied below said piston by a pipe 48, having an outlet 47, to retract the pusher upward. Said pipes are controlled by valves 53 which may be operated by levers 52. These levers are turned by a bar 51, having pin-and-slot connections with the levers (Fig. 5), and the bar is moved to the right (viewing said figure) by a solenoid 1^b and to the left by a solenoid 2^b. The arrangement is such that each solenoid 1^b opens one of the outlet pipes 46 or 47 when it opens one of the corresponding inlet pipes 48 or 45. The outlet pipes communicate with a pipe 44' (Fig. 8) leading to an open water tank T, from which a pump P returns the water to the pressure tank T', which supplies the pipe 44, the latter communicating with the inlet pipes 45, 48. The pusher being up and the carrier having advanced one step bringing a coking chamber under the pusher (Fig. 6), and the brakes 25 having been set, the pawl having dropped into a notch and the lever 87 having thrown the switch 5^a as seen in Fig. 16, the solenoid 2^b is energized and the bar 51 is thrown (to the right in Fig. 8 and left in Fig. 5) to open the fluid pressure pipe 45 and to close its outlet 46 and place the fluid pressure in pipe 45 in communication with the top of the pusher cylinder 49 and the valve 53 in pipe 48 is closed and valve 53 in pipe 47 opened to permit the fluid pressure in the cylinder 49 to drain to permit the downward movement of the piston. Thereupon the pusher discharges the coke in said chamber. The coke is received in a chute or hopper 59 located in the lower part of the coking region which is closed to the atmosphere by the seals 13 and 15. Said chute is provided with a rotary discharger 60 fixed on a shaft 61 which prevents the es-

cape of the gases resulting from the coking operation, and which is turned by a sprocket 52 on said shaft and suitable connections (not shown) to discharge the coke to a point outside the apparatus.

As soon as the pusher has reached its bottommost point it can be retracted upward without delay, and at this time the lever 58 operates the electric switch 4^a (Fig. 20), whereupon solenoid 1^b is energized so as to throw the bar 51 to the position shown in Fig. 5, whereupon fluid pressure is admitted into the lower part of the pusher cylinder 49 and the latter is returned upward to the position shown in said figure. When the pusher is at said lower position it also throws the switch 6^a from the position shown in Fig. 16 to the position shown in Fig. 21 thereby de-energizing the solenoid 2^b. When the pusher reaches its highest point it throws the switches 2^a, 8^a and 10^a thereby (Figs. 24, 27 and 28) respectively energizing the magnetic clutch and releasing the brakes for the next advancing step of the carrier.

The successive operations of the electric circuits controlled by the switches may be recapitulated as follows, with especial reference to Figs. 9 to 28, inclusive:

When the pawl drops into a notch, it moves lever 87 to throw the three-way switches 1^a, 3^a, 5^a, 7^a and 9^a. Switch 1^a breaks circuit to magnetic clutch, thereby disengaging the motor. Switch 3^a breaks circuit to solenoid 1^b, and switch 5^a makes circuit to solenoid 2^b. Solenoid 2^b opens and closes hydraulic valves, relieving pressure on under side of pusher piston and supplying pressure on top causing pusher to travel down. Switch 7^a makes circuit with solenoid 3^b opening inlet valve and closing outlet valve on brake cylinder, setting the brakes, and switch 9^a breaks circuit to solenoid 4^b (Fig. 8). When pusher piston reaches lowest position, switches 4^a and 6^a are thrown, making a circuit with solenoid 1^b and breaking circuit with solenoid 2^b, thus reversing the pressure in pusher cylinder, and causing pusher to travel up. When pusher reaches highest position, switches 2^a, 8^a, and 10^a are thrown, switch 8^a breaks circuit to solenoid 3^b and switch 10^a makes circuit to solenoid 4^b reversing the valve to brake cylinders and releasing brake. The spring on top of brake piston pushing brake free of brake shoe on machine. Switch 2^a closes the circuit with magnetic clutch, again starting the machine to rotate.

The pusher 50 is provided with a vertical guide casing 54 which is fastened to the superstructure by channel beams 55. The pusher cylinder 49 is supported from the superstructure by channels 56. The supporting plate 66 which extends from the filling station to the discharging station under the retorts 4 may be adjusted vertically relative to the under surface of the carrier to suit working

conditions. This plate is carried by supports 67 (Fig. 4) which are formed with slots 67' for that purpose.

At the under side of the carrier a gas seal 68 is provided as shown at the lower part of Fig. 7. This seal 68 is pivotally mounted on the support 69 and is so weighted as to gravitate into sealing position, the under surface of the carrier traveling along the upward pressing upper part of said seal, so that escape of the gases at this point from the coking region is prevented. On the top surface of the carrier a seal 70 bears downwardly thereon, this seal being movably anchored at one edge on the frame 71, and the other end of the same resting by its own weight on the top of the carrier. In order to prevent any wedging of the carrier, and material on the top surface of the latter, against this seal, the anchorage of the same is loose so that the seal may be readily swung around at its anchored end as well as rise at its free end. 72 is a thin flexible and corrugated metal sheet which is clamped to the seal 70 by the bar 73, and at its upper end is clamped between the frame 71 and a layer 74 of insulating material, the latter being overlaid by the cover 75 suitably attached to the frame 71. It will be understood that the seals 68 and 70 extend in a radial direction across the annular carrier, for the full width of the same, and they operate to separate (as to passage of gas) the coking region from the receptacle-heating region. There is also provided a side seal extending vertically along the outer peripheral surface of the carrier, as best seen in Fig. 4. This side seal is preferably formed of separate elements 76 pivotally connected with a vertical rod 79, the upper end of the latter being hung from the under side of the frame 78, by a T-head 76' or other suitable means. The seal sections 76 are pressed against the periphery of the carrier by springs 77 and sliding rods 77' to maintain a close contact at that point. A horizontal sectional view of this seal is shown in Fig. 2. It is or may be constructed like the seal 70 to yield outwardly at both edges, the gases which might pass its loose rear edge are intercepted by a plate 72' similar to the plate 72. It will be understood that the described gas seals may be applied at each side of the carrier where the heating region adjoins the coking region. But loose coking material on the top of the carrier and on the plate 66 may serve the purpose of the top and bottom seals at the charging side of the carrier. The said seals 68, 70 and 76 and corresponding seals at the other side of the carrier constitute means for obstructing the passage of gases of distillation from the coking region and also conserve the heat of this region.

The superstructure of the furnace is shown at S in Fig. 1 from which depend rods which sustain the flat arch brick s' of the furnace 130

cover or top, so that sections of said top may be removed as may be required.

80 is a channel frame fixed in the wall of the furnace (Fig. 2) in which is fitted the inspection door 81 above referred to, which is filled with insulating material 82. The gases resulting from the coking operation are taken away from the coking region through the outlet 88 for any desired recovery treatment.

10 The elements 4 which are preheated and thereafter impart their heat to the coking material are preferably constructed, as shown, to hold said material in relatively thin bodies so that the coking heat will be thoroughly imparted to said bodies in the time allowed by the progress of the carrier for the coking of each of said bodies. The process is a continuous one, although proceeding preferably by small steps of movement.

20 It will be observed that the carrier and the discharging means or pusher conjointly control the movable parts of the apparatus. For instance, a switch is thrown at a certain position in the movement of the carrier, and another switch is thrown at a certain point in the movement of the discharging means, and it is only as a result of the making of the electric circuit by both of these switches that the next desired movement of the parts takes place.

The invention as herein set forth may be variously embodied within the scope of the claims hereinafter made.

I claim:

35 1. The herein described process of coking carbonaceous material which consists in coking such material by moving coking receptacles progressively through a heating region and a coking region, imparting coking heat 100 to said receptacles in the heating region, charging material to be coked into the heated receptacles, then causing said material to be coked by the heat of said receptacles while passing through said coking region, then discharging the coked material from the said receptacles, and repeating said steps of heating, charging, coking and discharging in a continuous cycle; substantially as specified.

2. The herein described process of coking carbonaceous material which consists in coking such material by moving coking receptacles progressively and with intermittence of movement through a heating region and a coking region, imparting coking heat to 115 said receptacles in the heating region, charging material to be coked into the heated receptacles, then causing said material to be coked by the heat of said receptacles while passing through said coking region, then discharging the coked material from the said receptacles, and repeating said steps of heating, charging, coking and discharging in a continuous cycle; substantially as specified.

3. The herein described process of coking carbonaceous material which consists in cok-

ing such material by moving coking receptacles, having heating walls and having spaces for containing thin bodies of material, progressively through a heating region and a coking region, imparting coking heat to 70 said walls in the heating region, charging material to be coked into the heated receptacles, then causing said material to be coked by the heat of said walls while passing through said coking region, then discharging the coked material from the said receptacles, and repeating said steps of heating, charging, coking and discharging in a continuous cycle; substantially as specified.

4. The herein described process of coking 80 carbonaceous material which consists in coking such material by moving an endless series of coking receptacles progressively through a heating region and a coking region, imparting coking heat to said receptacles in the 85 heating region, charging material to be coked into the heated receptacles, then causing said material to be coked by the heat of said receptacles while passing through said coking region, then discharging the coked material from the said receptacles, and repeating said steps of heating, charging, coking and discharging in a continuous cycle; substantially as specified.

5. The herein described process of coking 95 carbonaceous material which consists in coking such material by moving coking receptacles progressively through a heating region and a coking region, imparting coking heat to said receptacles in the heating region, 100 charging material to be coked into the heated receptacles, then causing said material to be coked by the heat of said receptacles while passing through said coking region, and discharging gases from said material, confining 105 said gases from entrance into said heating region, and discharging the coked material from the said receptacles, and repeating said steps of heating, charging, coking and discharging in a continuous cycle; substantially 110 as specified.

6. In a coking apparatus, the combination of an endless series of coking receptacles having heating walls, gas-containing means forming a heating region and a coking region in which parts of the said series are located and from one to the other of which they may progressively move, means for supplying heat to said heating region, means for moving said receptacles from one of said regions to the other and thence to the first region, means for charging said receptacles after they are heated and before the coking operation, and means for discharging said receptacles after the coking operation; substantially as specified.

7. In a coking apparatus, the combination of an endless carrier, coking receptacles thereon having heating walls forming relatively thin chambers, gas-containing means 130

forming a heating region and a coking region in which parts of the carrier are located and from one to the other of which parts of said carrier may progressively move,
 5 means for supplying heat to said heating region, means for operating said carrier, means for charging said receptacles after they are heated and before the coking operation, and means for discharging said receptacles after the coking operation; substantially as specified.

8. In a coking apparatus, the combination of an endless carrier, coking receptacles thereon having heating walls, gas-containing means forming a heating region and a coking region in which parts of the carrier are located and from one to the other of which parts of said carrier may progressively move, means for supplying heat to said heating region, means for operating said carrier, means for charging said receptacles after they are heated and before the coking operation, and means for discharging said receptacles after the coking operation; substantially as specified.

9. In a coking apparatus, the combination of an endless carrier, coking receptacles thereon having heating walls forming relatively thin chambers, gas-containing means forming a heating region and a coking region in which parts of the carrier are located and from one to the other of which parts of said carrier may progressively move, means for supplying heat to said heating region, means for operating said carrier intermittently, means for charging said receptacles after they are heated and before the coking operations, and means for discharging said receptacles after the coking operation; substantially as specified.

10. In a coking apparatus, the combination of an endless carrier, coking receptacles thereon having heating walls forming relatively thin chambers, gas-containing means forming a heating region and a coking region in which parts of the carrier are located and from one to the other of which parts of said carrier may progressively move, means for supplying heat to said heating region, means for obstructing the passage of gas from one of said regions to the other, means for operating said carrier, means for charging said receptacles after they are heated and before the coking operation, and means for discharging said receptacles after the coking operation; substantially as specified.

11. In a coking apparatus, the combination of an endless carrier, coking receptacles thereon having heating walls, gas-containing means forming a heating region and a coking region in which parts of the carrier are located and from one to the other of which parts of said carrier may progressively move, means for supplying heat to said heating region, means for operating said carrier, means

for charging said receptacles after they are heated and before the coking operation, means for discharging said receptacles after the coking operation, and devices controlling the operating means of the carrier and dependent for their action on the positions of both the carrier and the discharging means; substantially as specified.

12. In a coking apparatus, the combination of an endless carrier, coking receptacles thereon having heating walls forming relatively thin chambers, gas-containing means forming a heating region and a coking region in which parts of the carrier are located and from one to the other of which parts of said carrier may progressively move, means for supplying heat to said heating region, means for operating said carrier, means for charging said receptacles after they are heated and before the coking operation, means for discharging said receptacles after the coking operation, and devices controlling the operating means of the carrier and dependent for their action on the position of both the carrier and the discharging means; substantially as specified.

13. In a coking apparatus, the combination of an endless carrier, coking receptacles thereon having heating walls, gas-containing means forming a heating region and a coking region in which parts of the carrier are located and from one to the other of which parts of said carrier may progressively move, means for supplying heat to said heating region, gas-obstructing means between the coking region and the heating region, means for operating said carrier, means for charging said receptacles after they are heated and before the coking operation, means for discharging said receptacles after the coking operation, and devices controlling the operating means of the carrier and dependent for their action on the positions of both the carrier and the discharging means; substantially as specified.

14. A process of low temperature distillation of carbonaceous material, consisting in preheating heating walls enclosing the mass of material by and in contact with the preheated walls, causing the processional advance of masses of such material from a charging station to a discharging station and through an enclosed region of distillation where the mass is subjected to distillation, while said masses are enclosed by and in contact with preheated walls, and successively forming and discharging said masses, and collecting the gaseous products; substantially as specified.

15. A process of low temperature distillation of carbonaceous material, consisting in preheating heating walls enclosing the mass of material by and in contact with the preheated walls, causing the processional advance of vertical relatively thin masses of such mate-

rial from a charging station to a discharging station and through an enclosed region of distillation where the mass is subjected to distillation, while said masses are enclosed by 5 and in contact with preheated walls, and successively forming and discharging said masses, and collecting the gaseous products; substantially as specified.

16. In a coking apparatus, the combination 10 of an endless carrier, coking receptacles thereon having heating walls forming chambers, gas-containing means forming a heating region and a coking region in which parts of the carrier are located and from one 15 to the other of which parts of said carrier may progressively move, means for supplying heat to said heating region, means for operating said carrier, means for charging said receptacles after they are heated and before 20 the coking operation, means for discharging said receptacles after the coking operation, and devices whereby the carrier and the discharging means conjointly control the movements of the carrier and discharging means; 25 substantially as specified.

17. In a coking apparatus, the combination 30 of an endless carrier, coking receptacles thereon having heating walls forming relatively thin chambers, gas-containing means forming a heating region and a distilling region in which parts of the carrier are located and from one to the other of which parts of said carrier may progressively move, means for passing heated gases in said distilling region 35 directly through and between said walls, means for operating said carrier, means for charging said receptacles after they are heated and before the distilling operation, means for discharging said receptacles after 40 the distilling operation, and devices automatically controlling the movements of the parts of the apparatus; substantially as specified.

18. In a coking apparatus, the combination 45 of an endless carrier, coking receptacles thereon having heating walls forming relatively thin chambers, gas-containing means forming a heating region and a distilling region in which parts of the carrier are located and from one to the other of which parts of said carrier may progressively move, means for passing heated gases in said distilling region 50 directly through said chamber, means for operating said carrier, means for charging said 55 receptacles after they are heated and before the distilling operation, means for discharging said receptacles after the distilling operation, and devices operated by said carrier and by said discharging means for automatically controlling the movements of the parts 60 of the apparatus; substantially as specified.

19. In a coking apparatus, the combination 65 of an endless carrier, coking receptacles thereon having heating walls forming chambers, gas-containing means forming a heating re-

gion and a coking region in which parts of the carrier are located and from one to the other of which parts of said carrier may progressively move, means for supplying heat to 70 said heating region, means for operating said carrier, means for charging said receptacles after they are heated and before the coking operation, means for discharging said receptacles after the coking operation and means for closing the bottoms of said chambers in the coking region, and leaving them open in the heating region; substantially as specified.

20. In a coking apparatus, the combination 75 of an endless carrier, coking receptacles thereon having heating walls forming chambers, gas-containing means forming a heating region and a coking region in which parts of the carrier are located and from one to the other of which parts of said carrier may progressively move, 80 movable gas-obstructing valves defining the limits of the said regions, means for supplying heat to said walls in said heating region, means for operating said carrier, means for charging said receptacles after they 85 are heated and before the coking operation, and means for discharging said receptacles after the coking operation; substantially as specified.

21. The herein described process of coking 90 carbonaceous material which consists in coking such material by moving spaced heating walls progressively through a heating region and then through a coking region, imparting coking heat to said walls in the heating re- 95 gion, charging material to be coked between the walls, then causing said material to be coked by the heat of said walls while passing through said coking region, and then discharging the coked material from between 100 said walls; substantially as specified.

22. The herein described process of coking 105 carbonaceous material which consists in coking such material by moving spaced heating walls progressively and with intermittance 110 of movement through a heating region and then through a coking region, imparting coking heat to said walls in the heating region, charging material to be coked between the walls, then causing said material to be coked 115 by the heat of said walls while passing through said coking region, and then discharging the coked material from between said walls; substantially as specified.

23. In a coking apparatus the combination 120 of a movable carrier having heat-storing members, stationary gas-containing means forming a heating region and a coking region in which parts of the carrier are located and from one to the other of which parts of said 125 carrier may progressively move, sealing means defining the limits of the said regions, said sealing means being supported for movement in substantially gas-tight relation by said stationary gas-containing means and be- 130

- ing adapted to press against said movable carrier during movement thereof and thereby prevent passage of gas between said sealing means and said carrier, means for supplying heat to said heat-storing members in said heating region, means for operating said carrier, means for charging said heating members after they are heated and before the coking operation, and coke discharge means for discharge of coke after the coking operation. 70
24. In a coking apparatus the combination of a movable carrier having heat-storing members, stationary gas-containing means forming a heating region and a coking region in which parts of the carrier are located and from one to the other of which parts of said carrier may progressively move, sealing means defining the limits of the said regions, 75 said sealing means being flexibly hinged in substantially gas-tight relation to said stationary gas-containing means and being adapted to press against said movable carrier during movement thereof and thereby preventing passage of gas from one to the other of said regions, means for supplying heat to said heat-storing members in said heating region, means for operating said carrier, means for charging said heating members after they are heated and before the 80 coking operation, and coke discharge means for discharge of coke after the coking operation. 85
25. In a coking apparatus the combination of a movable carrier having heat-storing members, stationary gas-containing means forming a heating region and a coking region in which parts of the carrier are located and from one to the other of which parts of said carrier may progressively move, sealing means defining the limits of the said region, 90 said sealing means being flexibly anchored at one portion thereof to said stationary gas-containing means in substantially gas-tight relation and being arranged and weighted so that another portion of said sealing means is adapted to press by gravity against said movable carrier during movement thereof and thereby prevent passage of gas from one to the other of said regions, means for supplying heat to said heat-storing members in said heating region, means for operating said carrier, means for charging said heating members after they are heated and before the coking operation, and coke discharge means for discharge of coke after the coking operation. 95
26. In a coking apparatus the combination of a movable carrier having heat-storing members, stationary gas-containing means forming a heating region and a coking region in which parts of the carrier are located and from one to the other of which parts of said carrier may progressively move, sealing means defining the limits of the said regions, 100 said sealing means including mechanism connected with and supported for relative movement in substantially gas-tight relation by said stationary gas-containing means and being adapted to press against said movable carrier, and spring means for pressing said mechanism against said movable carrier and adapted to maintain said mechanism in contact with said movable carrier under spring pressure during movement thereof and thereby prevent passage of gas between said sealing mechanism and said movable carrier, means for supplying heat to said heat-storing members in said heating region, means for operating said carrier, means for charging said heating members after they are heated and before the coking operation, and coke discharge means for discharge of coke after the 105 coking operation. 110
27. In a coking apparatus the combination of a movable carrier having heat-storing members, stationary gas-containing means forming a heating region and a coking region in which parts of the carrier are located and from one to the other of which parts of said carrier may progressively move, sealing means defining the limits of the said regions, 115 said sealing means including mechanism connected with and supported for relative movement in substantially gas-tight relation by said stationary gas-containing means and being adapted to press against said movable carrier, and spring means for pressing said mechanism against said movable carrier and adapted to maintain said mechanism in contact with said movable carrier under spring pressure during movement thereof and thereby prevent passage of gas between said sealing mechanism and said movable carrier, means for supplying heat to said heat-storing members in said heating region, means for operating said carrier, means for charging said heating members after they are heated and before the coking operation, and coke discharge means for discharge of coke after the 120 coking operation. 125
28. In a coking apparatus the combination of a movable carrier having heat-storing members, stationary gas-containing means forming a heating region and a coking region in which parts of the carrier are located and from one to the other of which parts of said carrier may progressively move, sealing means defining the limits of the said regions, 130 said sealing means including mechanism connected with and supported for relative movement in substantially gas-tight relation by said stationary gas-containing means and being adapted to press against said movable carrier, and spring means for pressing said

- mechanism against said movable carrier and adapted to maintain said mechanism in contact with said movable carrier under spring pressure during movement thereof and thereby prevent passage of gas between said sealing mechanism and said movable carrier, diaphragm means disposed between said mechanism and said gas-containing means and arranged to prevent passage of gas from 5 one to the other of said regions through the place of connection of said mechanism to said gas-containing means, means for supplying heat to said heat-storing members in said heating region, means for operating said carrier, means for charging said 10 heating members after they are heated and before the coking operation, and coke discharge means for discharge of coke after the 15 coking operation.
- 20 29. In a coking apparatus the combination of a movable carrier having heat-storing members, stationary gas-containing means forming a heating region and a coking region in which parts of the carrier are 25 located and from one to the other of which parts of said carrier may progressively move, sealing means defining the limits of the said regions, said sealing means comprising a device flexibly anchored at one portion there- 30 of to said stationary gas-containing means
- in substantially gas-tight relation and being arranged so that another portion thereof is adapted to press in substantially vertical direction against said movable carrier during movement thereof and devices flexibly anchored at one portion thereof to said stationary gas-containing means in substantially gas-tight relation and being arranged so that another portion thereof is adapted to press in transverse direction to said vertical direction against said movable carrier during movement thereof thereby preventing passage of gas from one to the other of said regions, means for supplying heat to said heat-storing members in said heating region, 40 means for operating said carrier, means for charging said heating members after they are heated and before the coking operation, and coke discharge means for discharge of coke after the coking operation. 50
30. Apparatus as claimed in claim 29, and which includes diaphragm means disposed between each of said devices and said gas-containing means and arranged to prevent passage of gas from one to the other of said regions through the place of anchorage for each said device.

In testimony whereof I have hereunto set my hand.

FRANZ PUENING.
